UNITED STATES PATENT OFFICE.

MENELIOUS PLATZ, OF ALMA, KANSAS.

CULTIVATOR.

SPECIFICATION forming part of Letters Patent No. 361,715, dated April 26, 1887.

Application filed February 19, 1887. Serial No. 228,256. (No model.)

To all whom it may concern:

Be it known that I, MENELIOUS PLATZ, a citizen of the United States, residing at Alma, in the county of Wabaunsee and State of Kansas, have invented a new and useful Improvement 5 in Corn-Cultivators, of which the following is a specification.

The invention relates to improvements in corn-cultivators, being adapted particularly 10 for the cultivation of listed corn; and its main objects are to provide an implement that will work satisfactorily in foul soil, or in soil where cornstalks have been cut and plowed under the surface.

15 The invention consists in the construction and novel arrangement of parts, hereinafter described, illustrated in the accompanying drawings, and pointed out in the claims hereto appended.

20 In the accompanying drawings, Figure 1 represents a perspective view of the machine; Fig. 2, a central longitudinal vertical section thereof. Fig. 3 is a plan view of the machine, and Fig. 4 detail perspective views to clearly 25 show the shape of the knives of two different shapes.

Referring to the drawings by letter, A designates the frame of the machine, composed of the transverse front and rear beams, *a a*, and 30 the two longitudinal beams *a' a'*, having their sides secured to the front and rear beams at equal distances from the center thereof.

B B are draft-chains, with their inner ends attached to plates secured to the ends of the 35 front beam of the main frame and with their front ends connected to a ring attached to the central loop of a single-tree, *b*.

C C are the runners, provided with similar 40 opposite notches near their front and rear ends, respectively, for the insertion of the lower sides of the front and rear beams of the main frame. The notches are deeper at their rear sides than at their front sides, so that the front and rear beams of the main frame are inclined edgewise, 45 and are stiffer under draft than if set as usual. The runners are rounded up at their front end, *c c*, as shown, are preferably iron-shod, and are rendered both vertically and laterally adjustable with reference to the main frame by 50 means of plates D D, which are bent to fit in between the meeting-points of the runners and the front and rear beams of the main frame,

and provided in their horizontal leaves with the slots *d d* and in their vertical leaves with the slots *d' d'*. By means of the slots *d d* and proper set-screws passing therethrough and engaging the beams of the main frame, the runners can be adjusted laterally thereon, and by means of the slots *d' d'* and set-screw passing therethrough and engaging in the runners the latter can be adjusted vertically upon the main frame. The runners are adjusted laterally by the means described to fit any width of furrow.

E E are knives attached to the outer sides 65 of the outer surfaces of the runners at similar parts thereon. Near their front ends the same knives incline rearward and near their points turn upward, and are also inclined downward from back to edge. The bent-up inner end is 70 pivoted at *e* upon the runners, and provided with slots *e'*, made on the arcs of circles of which the pivots *e* are centers, by means of which slots and proper set-screws passing therethrough the knives can have their inclination from back to edge adjusted to different 75 angles, as convenient or necessary.

F F are knives, an equal number of which are secured upon the opposite arms of a transverse bar, *f*, which has partial rotation in bearings *f'* on the upper edge of the longitudinal beams *a'* of the main frame, between the front and rear beams thereof. The bar *f* is preferably rectangular in cross-section, and is cut away or rounded at proper points to form 80 journals for the bearings *f'*. The backs of the knives F curve rearward, downward, and inward, and their edges run rectangularly rearward and downward.

G G are hooks secured to the upper surface 90 of the bar *f*, equally distant from its center, within the beams *a'*. The said hooks engage the looped ends of the rods H H, which run through openings in the upturned inner ends of the spring-plates *h h*, the outer ends of which 95 are firmly secured to the rear beam of the main frame.

H H are coiled springs surrounding the rods 100 H between their outwardly-bent rear ends (or collars on said ends) and their upwardly-bent front ends, against which the springs bear, thus tending to rotate the bar *f* and affixed knives downward.

The bar and knives are rotated upward

against the action of the springs by the following means:

1 I is a frame composed of the two inclined meeting legs i i' , respectively secured to and 5 extending from the front and rear beams of the main frame, and the angular brace-plate i^2 , secured to the rear leg, i' .

2 J is an angular lever pivoted at its angle within a longitudinal slot, j , in the front leg, i , and 10 having connected to the end of its forwardly-extending leg j' a link-rod, j^2 , the lower end of which is connected to the end of the forwardly-extending arm j^3 , secured centrally to the bar f . By moving the handle of the lever upward or rearward the knives F and bar f are 15 rotated downward.

3 To retain the knives as set, the curved rack K is secured to the leg i adjacent to the lever J , the teeth of which rack are engaged by a 20 pawl, k , sliding in a director, and having its upper end connected by a link, k' , with the lower arm of the hand-lever k^2 , pivoted on the lever J .

4 The runners act as fenders to the young corn 25 between them and prevent the soil loosened and cut up by the knives from covering the same, and, as described, are adjustable to furrows of different widths, so that the driver can force the knives E into the ridges between 30 the rows to any desired depth. The said knives, on account of their inclination from back to edge, are forced down in the ridges by the forward movement of the machine, and when clear of the ridges quickly free themselves from rubbish.

5 The knives F , being under control of the driver, can be raised by the described means to clear them of rubbish, or when the machine is being turned or transported.

40 The spiral springs will permit the knives to ride over any obstruction without being injured, after which they will return to their original position. If desired, each knife may be connected with a separate spring; but the 45 described construction is preferred.

50 The machine may be attached to any cultivator or listing machine, and the inclination of the knives E from back to edge forces them into the ridges and prevents the machine from riding over the surface.

55 The ends of the front and rear beams of the main frame will act as crushers, pulverizing all lumps in the ridges over which they pass. The inclination of the under surfaces of said beams will aid this action, as the beams will ride upon the said lumps.

On account of the described formation, the knives F throw the earth inward from knife to knife and toward the runners, so as to pulverize and spread it between the ridges.

60

Having described my invention, I claim—

1. The combination, with the main frame and the knives, constructed and arranged substantially as described, of the runners rounded on their front ends, vertically and laterally 65 adjustable with reference to the main frame, and acting as fenders to the young corn to prevent the same being covered by the broken and loosened soil, substantially as specified.

2. The combination, with the main frame 70 provided with front and rear beams having their front sides tilted up, substantially as described, of the runners laterally adjustable on the main frame, and the knives pivoted to the outside of the runners, inclined rearward 75 therefrom, having their outer ends turned upward and inclined downward from back to edge, and having said transverse inclination adjustable on the runners by means of slots and set-screws, substantially as specified.

80

3. The combination, with the main frame, the adjustable runners, and the adjustable knives secured to the runners, of the oscillating bar journaled upon the main frame, the knives secured thereto, having their edges inclined rearward and downward and their backs curved rearward, backward, and inward to throw the pulverized earth inward, and mechanism, substantially as described, whereby the driver is enabled to oscillate said 90 bar and raise and lower said knives, substantially as specified.

85

4. The combination, with the main frame, oscillating bar journaled thereon, and knives secured to said bar, of the hooks secured to 95 the upper surface of said bar, the rods with the looped ends engaging said hooks, the spring-plates holding said rods, the coiled springs surrounding the rods and acting against the upturned ends of the spring-plates, and mechanism, substantially as described, whereby the knives can be moved and held upward against the action of said coiled springs, substantially 100 as specified.

100

In testimony that I claim the foregoing as 105 my own I have hereto affixed my signature in presence of two witnesses.

MENELIOUS PLATZ.
